[57] CLAIM

The ornamental design for a battery case, as shown and described.

DESCRIPTION

FIG. 1 is an exploded perspective view of a battery case showing my new design;

FIG. 2 is a rear elevational view of the mounting block

portion thereof, the rear fitting against the front of the battery pack;

FIG. 3 is a right-hand side view of the mounting block portion thereof;

FIG. 4 is a front elevational view of the mounting block portion thereof;

FIG. 5 is a left-hand side view of the mounting block portion thereof;

FIG. 6 is a top plan view of the mounting block portion thereof;

FIG. 7 is a bottom plan view of the mounting block portion thereof;

FIG. 8 is a front elevational view of the battery pack portion thereof;

FIG. 9 is a rear elevational view of the battery pack portion thereof;

FIG. 10 is a left hand side view of the battery pack portion thereof;

FIG. 11 is a top plan view of the battery pack portion thereof;

FIG. 12 is a bottom plan view of the battery pack portion thereof;

FIG. 13 is a front elevational view of the battery case on an enlarged scale;

FIG. 14 is a top plan view thereof;

FIG. 15 is a bottom plan view thereof; and

FIG. 16 is a left side view thereof.
